DEVICE FOR COMPUTING AND INDICATING
TIME INTERVALSGordon Tucker, Minneapolis, Minn., assignor to
E. Roberts

Application February 2, 1934, Serial No. 709,512

22 Claims. (Cl. 40—110)

This invention relates to devices for computing and indicating time intervals. Such devices, while not limited thereto, have utility in determining visibly the periods of sterility and fertility of women whose menstrual cycles are known by observation.

For a more complete understanding of the nature of the time intervals capable of computation and indication by devices in accordance with the present invention, as well as of the reasons therefor, reference is made to the work entitled "The Rhythm of Sterility and Fertility in Women", Third Edition, 1933, by Leo J. Latz, M. D., published by Latz Foundation, Chicago, Illinois. Briefly, the conclusions reached by Latz and his colleagues in this field of research are to the effect that the menstrual cycle has two periods of sterility and an intermediate period of fertility. The first period of sterility may be regarded as running from the first through the eleventh day, inclusive, preceding the day that menstruation is expected to occur. The fertile period runs from the twelfth day, inclusive, back to the nineteenth day preceding expected menstruation, with the second sterile period running from the twentieth to the beginning of the menses of this cycle and thus completing the cycle.

Thus with a 28-day menstrual cycle and the menses commencing on the first day of the month, the second and first sterile periods are comprised respectively by the days numbered 1 through 9, inclusive, and 18 through 28, inclusive. The fertile period is comprised of the days running from the 10th to the 17th, inclusive.

The computation of these periods is complicated by the fact that the menstrual cycle of a woman may vary, that is to say, the cycle may occur regularly but at intervals less than or greater than 28 days. Also, the cycle may vary from month to month; that is to say, a 28-day cycle may be followed by a 31-day cycle. In the first condition of variance, the first sterile period (the period in advance of the expected menstruation) and the fertile period are computed in the same manner as in the 28-day cycle above set forth, with the second period of sterility (following the last menstruation) being less or greater as the cycle is less or greater. Under the second condition of variance and under the assumption that the cycle varies between 28 and 31 days, three days must be added to the fertile period to run in addition to the fertile period as computed with a 31-day cycle, so that instead of an 8-day period of fertility this period would be extended to 11 days.

It will be obvious from the above that great care must be exercised in computing the various periods and, further, that the computations are, when measured by an ordinary calendar, of a confusing nature.

Accordingly an object of the present invention is the provision of a device for computing the aforesaid periods in a reliable, simple and efficient manner. A further object is the provision of a device of the above character which indicates visibly the aforementioned periods within a given menstrual cycle. A further object is the provision of a device of the above character which is sufficiently flexible as to compute the periods under consideration within the cycle where the cycle varies of itself or in relation to a following cycle.

Other objects will be in part obvious and in part hereinafter pointed out in connection with the following analysis of this invention, wherein is illustrated one of various possible embodiments of the present invention, together with certain modifications in detail.

In the drawing

Fig. 1 is a plan view of the device in accordance with the present invention and set for a regular 28-day menstrual cycle.

Fig. 2 is a section along lines 2—2 of Fig. 1.

Figs. 3, 4 and 5 are, respectively, detail views of three indicator units shown in assembled relation on the calendar disc in Fig. 1.

Referring to the drawing, reference character 10 indicates a circular calendar disc of suitable material such as cardboard, composition material as bakelite, metal, or the like, having a peripheral band portion 11, a calendar portion 35 12 separated from the band portion by an annular strip 13 of "hill and dale" configuration as will be further referred to, and a center portion 14. By reference to Fig. 2, the disc is centrally apertured as at 15, the aperture receiving the 40 tubular stem 16 of a cup 17, with the cup being rigidly fixed to the disc 10.

Referring to the calendar portion 12 of the disc, such portion is defined by five concentric circles 20, the circles being equi-distantly spaced 45 and inscribed from the center of disc 10. The circles 20 are sub-divided into arcs by the radial lines 21 from the center of the disc, the radii 21 being equi-distantly spaced. The radii divide each of the four angular bands defined by circles 50 20 into 62 equal segments, with the arc of each segment being 1/62nd of the circumference of the circles.

Numbering the four annular bands from the outer to the inner portion as I, II, III and IV 55

and starting at the line x , circle I is used for those months of the year that have 31 days (January, March, May, July, August, October and December). Circle II is used for those months of the year that have 30 days (April, June, September and November). Circle III is used for the month of February during leap year, a 29-day month; and circle IV is used for the month of February when it contains 28 days. Circle I has a sequence of numbers 1-31, 1-31; circle II has a sequence of numbers 1-30, 1-31, 1; circle III has a sequence of numbers 1-29, 1-31, 1-2; circle IV has a sequence of numbers 1-28, 1-31, 1-3.

Considering now the means for computing and indicating time intervals on the calendar above described, reference character 25 indicates an indicator unit consisting of a hub 26 (Figs. 2 and 3) and two angularly disposed arrow arms 27, 28, the center lines of which subtend an arc of 18/62nds of the circumference of circles 20. Intermediate their ends, the arrow arms 27, 28 are connected by an arcuate band 30, the band extending substantially beyond arrow 27 in an anti-clockwise direction, as at 31. The indicator unit 25 is mounted to turn on an axis which extends through the center of disc 10.

The extension 31 of the arcuate band 30 has inscribed thereon a plurality of radial lines 32, seven in number in the construction illustrated, 30 thus forming six segmental sub-divisions designated as A, B, C, D, E, F. Said radial lines 32 are equi-angularly spaced from each other and their angular spacing corresponds to the spacing of the radial lines 21 aforesaid. The medial line of space F is so related to the center line of arrow arm 27 that as the latter coincides with the medial line of a row of segments of calendar portion 10, the medial line of space or segment F will coincide with that of the next row, in an anti-clockwise direction, of segments of the calendar portion.

Intermediate the arrow arms 27, 28 the arcuate band is provided with sub-divisions or segments defined by radial lines 33, of which segment 34 is 3/62nds of the circumference, segment 35 is 4/62nds of the circumference, and segment 36 is 2/62nds of the circumference. Segmental division 36 may be designated by the marking G, following which, in a clockwise direction, are the segments 37, marked H, I, J, K, L, each following an arc of 1/62nd of the circumference. The aforesaid segmental portions are so related to the center line of arrow arm 27 that when this center line coincides with a medial line of a row 50 of segments in the calendar portion, the radial lines 33, if extended, would coincide with radial lines 21 which define said segments. The arcuate band 30 and the extension 31 may be provided with edge flanges 29 and 39, respectively, which 60 extend relatively upwardly and inwardly to form a guide and retaining trackway for the purpose to be described.

A second indicator unit, also movable on an axis extending through the center of the disc, is generally indicated at 40 and comprises a hub 41 (Figs. 2 and 4), an arrow arm 42 extending therefrom, and an arcuate or segmental band 43 offset from and extending intermediate the ends of the arrow arm in a clockwise direction. Said extension 43 is adapted to overlap the extension 31 of indicator unit 25 with the unit 40 being adjustable thereover and guided by the trackway formed by flanges 39. On the under face of the extension 43 is a lug or detent 44 adapted to fit into depressions or apertures 45 formed in the segmental

divisions A to F inclusive, and it will be understood that as indicator unit 40 is pressed towards the face of the disc 10, with the detent 44 engaging in a recess 45 of the series, the indicator units 25 and 40 are held in desired adjusted position with respect to each other. The arrow arm 42 may contain markings such as 31, 30, 29, 28 which relate to circles I, II, III and IV, to indicate clearly the number of days in the month comprehended with the respective circles.

10

A third indicator unit, also movable on an axis extending through the center of the disc, may comprise a hub 47 (Figs. 2 and 5) with an arrow arm 48 extending therefrom and an arcuate or segmental band 50 offset from and extending from 15 said arm intermediate its ends and in a clockwise direction. Said segmental portion 50 is arranged to overlap the arcuate band 30 of indicator unit 25, with the unit 46 being adjustable thereover and guided by the trackway formed by flanges 29. 20 The said portion 50 is provided on its under face with a detent 51 adapted to engage in one of a series of depressions or apertures 52 formed in certain of the segments 31 of arcuate band 30 and in a portion of the band adjacent thereto. As unit 25 46 is pressed towards the face of disc 10, it will, by engagement of detent 51 in a depression 52, be held in desired adjusted position on unit 25.

Considering now the mounting of the various indicator units of the calendar disc 10, one such 30 form of mounting is illustrated in Fig. 2 and may be described as follows: The hubs 26, 41 and 47 of units 25, 40 and 46, respectively, are mounted on a sleeve 55 having an end flange 56 against which hub 47 may bear. Hubs 41 and 47 are rotatable on said sleeve while hub 26 may be fixed thereto. A spring cap 57 is fixed to sleeve 55 by bending over the end of the sleeve, as indicated at 58, or by other suitable means. The spring cap 57 is provided on its outer circular wall with a 40 plurality of teeth or serrations 60 which are adapted to interfit with like teeth or serrations formed in a vertical wall of the cup 17 secured to the disc 10. The spring construction of cap 57 thus permits a frictional engagement between said 45 cap and the cup 17 when the cap is fitted into the cup with the teeth or serrations 60 preventing free turning of the cap relative to the cup 17.

Sleeve 55 and cap 57 are removably secured to the cup by means of a stud 61 extending there- 50 through and having its end threaded as at 62 to engage with threads formed in the bore of stem 15. The other end of stud 61 has secured thereto a knurled or equivalent nut 64 through the medium of a screw 65.

By the aforesaid assembly, the sleeve 55 with the indicator units carried thereby and the spring cap 57 are rotatably carried by stud 61. To mount the indicator units on the disc 10, the spring cap 57 is pressed into the cup 17 and the stud 61 forced 60 through sleeve 55 until its end threads engage the threads on the hollow stem 15, whereupon stud 61 is turned. Consequently, the entire mounting assembly will be secured fast to the cup 17 and disc 10.

55

When it is desired to reset the indicator and particularly indicator unit 25, nut 64 is turned to unthread stud 61 whereupon the sleeve 55 and cap 57 may be bodily withdrawn from cup 17 whereupon indicator unit 25 and sleeve 55 may 70 be turned about the axis of stem 61 to desired position and again secured to the cup 17 and its stem 15 in the manner above described.

By reference to Fig. 2, the arrow arms 27, 28, 42 and 48 are made advantageously of spring 75

metal and their outer ends bowed. Thus, as nut 64 is tightened, and with the various arrows set in their proper position, the hubs of the indicator units are moved axially, with the face of the disc preventing such movement of the ends of the arrow. Accordingly, the free ends of the arrow arms are put under strain and by this means are frictionally held in said position against the face of the disc. Further, the length of the arrow arms is such that their spring ends engage, when properly set, in the depressions of the "hill and dale" strip 13 formed in disc 10. Consequently, inadvertent or unintentional movement of the arrow arms, after proper setting, is impossible.

Locking of the indicator unit 25 may be further accomplished through the medium of a pin 68 carried at the free end of a leaf spring 69 riveted or otherwise secured to said unit and preferably to the arrow arm 27 thereof, the locking pin 68 extending through a suitable aperture in the unit and being of sufficient length as to engage in one of a series of holes 70 punched in the central portion 14 of disc 10. The pin 68 may drop into one of the holes 70 as the unit 25 is brought to desired position of adjustment and thus holds the parts against relative rotation.

In use of the device aforesaid, the setting of the device to arrive at the computations and indications contemplated will now be explained, with the setting illustrated in Fig. 1 being that for a regular 28-day cycle. In this setting I have departed somewhat from the findings of Latz above referred to in that while Latz maintains that a period of sterility of 11 days exists prior to the day when menstruation is expected, I have, to provide an added factor of safety, cut down this period to ten days. In further explanation, my device is capable of computing the periods of sterility and fertility for menstrual cycles of 26 to 31 days, inclusive, with the segments A, B, C, D, E, F representing the 31, 30, 29, 28, 27 and 26 day cycles, respectively. Assuming that a 28-day cycle has been determined by observation, unit 40 is moved over extension segment 31 and guided by the flanges 39 thereof to cover the segmental portion C (29-day cycle) and uncover the portion D (28-day cycle) and with unit 40 held to unit 25 in this adjusted relation, as permitted by the mounting of the parts as aforesaid, the device is now ready to indicate the computations arrived at. For this condition of a regular menstrual cycle, unit 46, which is carried on unit 25, has been set to cover segments H—L inclusive, and to uncover segment G, which setting is the same for regular cycles, regardless of their length. Assuming that menstruation commences on the second day of a 31-day month, the indicating units 25 and 40 are moved about the axis of disc 10 until arm 42 indicates the second day of circle I (31-day month). Under this condition arrow arms 42 and 27 define an arc of 10 days, that is, the second day through the tenth day, representing the second sterile period, previously mentioned. Segments 34, 35, 36 define an arc of nine days, that is, from the eleventh through the nineteenth day. This arc indicates the days included in the period of fertility, and segments 34, 35 and 36 may be suitably colored and marked to make this period and the days included therein readily distinguishable. If desired, the segment 35 may carry suitable indicia such as "Most Fertile", which will indicate four days (the fourteenth through the seventeenth), indicating the most fertile sub-division of the fertile period.

Arrow arms 48 and 28 define an arc of ten

days, that is, from the twentieth inclusive through the twenty-ninth day and represents the days included in the first sterile period as referred to in the foregoing. The aforesaid completes the menstrual cycle with the expected menstruation to commence on the thirtieth day of the month.

Where the menstrual cycle is less or greater than the 28-day cycle above treated but with the cycle regular, indicator unit 40 is moved relatively of unit 25, with the result that the second sterile period is increased or decreased while indicator unit 46 is undisturbed due to the observed regularity of the cycle. Thus, if a regular cycle of 30 days has been observed, unit 40 is shifted to cover segment A, but to uncover segment B, and such a setting will lengthen the second sterile period by two days. Conversely, if a 26-day cycle has been observed, unit 40 is shifted to cover segment E, so leaving uncovered the segment F which indicates the 26-day cycle, with the result that the second sterile period is correspondingly shortened.

It will be understood that the setting of the device for a regular cycle with menstruation to commence in a 30-day month, or in February of a leap year, or in February of intermediate years, the same operations of setting the unit 40 relative to unit 25 and of adjusting said units to the day on which menstruation is to commence is the same as that considered above, although readings in those cases will be made on circles II, III and IV, respectively, rather than on circle I.

Considering now the use of the device of the present invention where the cycle may vary from month to month, unit 46 is adjusted with respect to unit 25 to give an indication of the fertile period. If, for example, the cycle has been found to vary from a 28-day cycle to a 31-day cycle, a difference of three days, unit 40 is adjusted to the 28-day cycle as if the cycle were regular as aforesaid, by covering segment C and uncovering segment D. Thereupon, unit 46 is adjusted in a clockwise direction to uncover three segments, H, I, J, with the result that the fertile period is extended for three days, and under the assumption of the menses commencing on the 2nd day of the month, the fertile period under the condition of irregularity above set forth, will run from the eleventh through the twenty-second day. It will be observed that arrow arm 28 does not move to complete the possibly long cycle of 31 days which might occur, but inasmuch as the fertile period is well established, and as the first sterile period runs to the expected menstruation, whether it occurs on the 28th or the 31st day, such is not particularly material. However, where such an added indication is desired, unit 46 could be extended and provided with an additional arrow arm so related as to overlie arrow arm 28 when unit 46 is adjusted for a condition of regularity, that is, as shown in Fig. 1 and as previously described. Thus, as unit 46 is moved clockwise for a one-day, two-day, or greater observed irregularity, the additional arm would move past arrow arm 28 to indicate the day when the cycle is to be complete, with the menses commencing on the day following.

Without further analysis the foregoing will so fully reveal the gist of this invention that others can by applying current knowledge readily adapt it for various applications without omitting certain features that, from the standpoint of the prior art, fairly constitute essential characteristics of the generic or specific aspects of this invention, and therefore such adaptations should

and are intended to be comprehended within the meaning and range of equivalency of the following claims.

I claim:

- 5 1. In a device of the character described, a disc
having a circular band thereon subdivided into a
plurality of segments, the segments being num-
bered serially, and a plurality of indicator units
mounted to turn on an axis extending through the
10 center of the disc, one of said units including an
arcuate band, a second unit including an arcuate
band adapted to be adjustably related to an end
portion of said first-named band and an indicator
15 arm extending to said circular band, the first-
named arcuate band having provisions for estab-
lishing a plurality of said numbered segments in
relation to a determined segment established by
said indicator arm.

20 2. In a device of the character described, a disc
having a circular band thereon subdivided into a
plurality of segments, the segments being num-
bered serially, an indicator unit mounted to
turn on an axis extending through the center of
25 the disc, said unit including an arcuate band and
an indicator arm extending to said circular band,
and a second indicator unit including an arcuate
band adapted to be adjustably related to an end
portion of said first-named arcuate band and an
30 indicator unit extending in the direction of said
numbered segments, said first-named arcuate
band having provisions for establishing a plural-
ity of said numbered segments in relation to a
determined segment established by the position
35 of the indicator arm of said second unit.

40 3. In a device of the character described, a disc
having a circular band thereon subdivided into a
plurality of segments, the segments being num-
bered serially, an indicator unit mounted to turn
on an axis extending through the center of the
45 disc, said unit including an arcuate band and an
indicator arm extending intermediate the ends of
said band to said numbered segments, and a sec-
ond indicator unit including an arcuate band
adapted to be adjustably related to one end por-
50 tion of the first-named arcuate band and an indi-
cator arm extending to said numbered segments,
the other end portion of said first-named arcuate
band having provisions for establishing a plural-
ity of said numbered segments in relation to a
55 determined segment established by the position
of the indicator arm of the second unit.

60 4. In a device of the character described, a disc
having a circular band thereon subdivided into a
plurality of segments, the segments being num-
bered serially, and a plurality of indicator units
65 mounted to turn on an axis extending through
the center of the disc, one of said units including
an arcuate band, a second unit including an arcuate
band adapted to be adjustably related to
70 an end portion of said first-named band and an
indicator arm extending to said circular band, the
first-named arcuate band having provisions for
establishing a plurality of said numbered seg-
ments in relation to a determined segment estab-
75 lished by said indicator arm, and a third indi-
cator unit including an arcuate band adapted to
be adjustably related to the other end portion of
said first-named arcuate band and cooperating
with said provisions to increase the number of
80 said segments established thereby.

85 5. In a device of the character described, a disc
having a circular band thereon subdivided into a
plurality of segments, the segments being num-
bered serially, an indicator unit mounted to turn
90 on an axis extending through the center of the

disc, said unit including an arcuate band and an indicator arm extending to said circular band, and a second indicator unit including an arcuate band adapted to be adjustably related to an end portion of said first-named arcuate band and an indicator arm extending in the direction of said numbered segments, said first-named arcuate band having provisions for establishing a plurality of said numbered segments in relation to a determined segment established by the position of the indicator arm of said second unit, and a third indicator unit including an arcuate band adapted to be adjustably related to the other end portion of said first-named arcuate band and cooperating with said provisions to increase the number of said segments established thereby. 5 10 15

6. In a device of the character described, a disc having a circular band thereon subdivided into a plurality of segments, the segments being numbered serially, an indicator unit mounted to turn 20 on an axis extending through the center of the disc, said unit including an arcuate band and an indicator arm extending intermediate the ends of said band to said numbered segments, and a second indicator unit including an arcuate band 25 adapted to be adjustably related to one end portion of the first-named arcuate band and an indicator arm extending to said numbered segments, the other end portion of said first-named arcuate band having provisions for establishing a 30 plurality of said numbered segments in relation to a determined segment established by the position of the indicator arm of the second unit, and a third indicator unit including an arcuate band adapted to be adjustably related to the other end 35 portion of said first-named arcuate band and co-operating with said provisions to increase the number of said segments established thereby.

7. In a device of the character described, a disc having a circular band thereon subdivided into a plurality of segments, the segments being numbered serially, an indicator unit mounted to turn on an axis extending through the center of the disc, said unit including an arcuate band and an indicator arm extending to said circular band, a second indicator unit comprising an indicator arm extending to said circular band and an arcuate band adapted to be adjustably related to one end portion of the first-named arcuate band whereby said indicator arms may define an arc of said circular band as permitted by said adjustment, and a third indicator unit including an indicator arm extending to said circular band and adjustably related to the other end portion of the first-named arcuate band, said indicator arms of the first and third-named units establishing a plurality of said numbered segments in relation to a segment established by the indicator arm of the second-named unit.

8. In a device of the character described, an element having a circular calendar portion comprising four concentric bands and the bands being each subdivided into sixty-two equal segments, with the segments of the bands being disposed radially, the segments of the bands being further numbered serially from a common radius in accordance with the four length conditions of adjacent months of the year, and a plurality of indicator units mounted to turn on an axis extending through the center of the calendar portion, one of said units being settable with relation to another unit, and along a radial row of segments, and said other unit defining an arc along said calendar portion, whereby to establish

a period of a plurality of numbered days within said arc.

9. In a device of the character described, an element having a circular calendar portion comprising four concentric bands and the bands being each subdivided into sixty-two equal segments, with the segments of the bands being disposed radially, the segments of the bands being further numbered serially from a common radius in accordance with the four length conditions of adjacent months of the year, and a plurality of indicator units mounted to turn on an axis extending through the center of the calendar portion, two of said units being settable with relation to a third unit, whereby to establish a period of a plurality of numbered days within an arc along said calendar portion as indicated by two of said units.

10. In a device of the character described, an element having a circular calendar portion comprising four concentric bands and the bands being each subdivided into sixty-two equal segments, with the segments of the bands being disposed radially, the segments of the bands being further numbered serially from a common radius in accordance with the four length conditions of adjacent months of the year, and a plurality of indicator units mounted to turn on an axis extending through the center of the calendar portion, two of said units being carried by and settable with relation to a third unit, whereby to establish a plurality of numbered days within an arc along said calendar portion as indicated by two of said units.

11. In an indicator, a data carrying element having a mounting member, a sleeve, a plurality of indicator units, one of said units being fixed to the sleeve and another unit being carried by said first unit and rotatable on the axis of the member, and means for securing detachably the sleeve to the member.

12. In an indicator, a data carrying element having a mounting member, a sleeve, a plurality of indicator units, one of said units being fixed to the sleeve and another unit being carried by said first unit and rotatable on the axis of the member, a cap fixed on the sleeve and seating in the mounting member, and means for securing detachably the cap to the mounting member.

13. In an indicator, a data carrying element having a mounting member, a sleeve, a plurality of indicator units, one of said units being fixed to the sleeve and another unit being carried by said first unit and rotatable on the axis of the member, a cap fixed on the sleeve and adapted to seat in the mounting member, means cooperating between the cap and the member whereby to hold said first unit in desired angular position, and means for actuating said cap axially of said member whereby to seat the cap in the member.

14. In an indicator, a data carrying element having a mounting member, a sleeve, a plurality of indicator units, said units having portions of springy material adapted to engage said element, one of said units being fixed on said sleeve, another unit being carried by said first unit and rotatable on the axis of the sleeve, and means for actuating the sleeve and units axially against the resistance of the springy material of said units to said actuation, said means being operative to secure the sleeve to the mounting member and to resiliently hold the units in desired position relative to the data carrying element.

15. In an indicator, a data carrying element,

an indicator unit rotatable on an axis extending through said element, means for securing detachably the unit to the element including provisions for actuating the unit in the direction of the axis on which it is rotatable, and means responsive to such actuation to hold the unit against rotation on said axis.

16. In an indicator, a data carrying element, an indicator unit rotatable on an axis extending through said element, means for securing detachably the unit to the element including provisions for actuating the unit in the direction of the axis on which it is rotatable, and cooperating means on said element and said unit and responsive to such actuation to hold the unit against rotation on said axis.

17. In an indicator, a data carrying element, a mounting cup secured thereto and having serrations on its inner wall, an indicator unit, and means carrying said unit and having provisions cooperating with the serrations of the cup for holding the unit against rotation.

18. In a device of the character described, an element providing a circular band subdivided into a plurality of segments, the segments being numbered serially, an indicator unit movable on said element, said unit providing a band portion cooperatively related to said circular band, a second indicator unit adjustably related on said first unit and having an indicator for indicating a segment of said circular band and the first-named unit having provisions for establishing a plurality of numbered segments on said circular band in relation to a determined segment established by the indicator of said second unit.

19. In a device of the character described, an element providing a circular band subdivided into a plurality of segments, the segments being numbered serially, an indicator unit movable on said element, said unit providing a band portion cooperatively related to said circular band, a second indicator unit adjustably related on said first unit and having an indicator for indicating a segment of said circular band, and a third indicator unit adjustably related on said first unit, said first and third units each provided with an indicator operative to establish therebetween a plurality of numbered segments on said circular band in relation to a determined segment established by the indicator of said second unit.

20. In a device of the character described, an element providing four concentric bands and the bands being each subdivided into sixty-two equal segments, with the segments of the bands being aligned, the segments of the bands being further numbered serially from an aligned row of segments in accordance with the four length conditions of adjacent months of the year, and a plurality of indicator units mounted for movement on said element, one of said units being settable with relation to another unit to designate the aligned segments of a row and said other unit establishing a plurality of segments along the arc of the bands and in relation to a segment of the row of segments designated by said first unit.

21. In a device of the character described, an element providing four concentric bands and the bands being each subdivided into sixty-two equal segments, with the segments of the bands being aligned, the segments of the bands being further numbered serially from an aligned row of segments in accordance with the four length conditions of adjacent months of the year, and a plurality of indicator units mounted for movement

on said element, two of said units being settable with relation to a third unit whereby to establish a period of a plurality of numbered days along the arc of the bands as indicated by two of said units in relation to another unit.

5 22. In a device of the character described, an element providing four concentric bands and the bands being each subdivided into sixty-two equal segments, with the segments of the bands being 10 aligned, the segments of the bands being further numbered serially from an aligned row of seg-

ments in accordance with the four length conditions of adjacent months of the year, and a plurality of indicator units mounted for movement on said element, two of said units being carried by and adjustable with respect to a third unit, whereby to establish along the arc of said bands a period of a plurality of numbered days as indicated by two of said units in relation to another unit.

5 GORDON TUCKER. 10
